UNITED STATES PATENT OFFICE.

GUSTAVE ERIC ERICKSON, OF SIOUX CITY, IOWA.

ASH SIFTER.

Application filed August 13, 1919. Serial No. 317,202.

To all whom it may concern:

Be it known that I, GUSTAVE ERIC ERICKSON, a citizen of the United States, residing at Sioux City, in the county of Woodbury 5 and State of Iowa, have invented certain new and useful Improvements in Ash Sifters; and I do hereby declare the following to be a full, clear, and exact description of the invention, such as will enable others 10 skilled in the art to which it appertains to make and use the same.

This invention relates to ash sifters and the primary object of the invention is to provide an improved ash sifter in which the 15 parts thereof are completely enclosed, so as to render the device dust-proof and thereby eliminating the scattering of ashes during the sifting process.

Another object of the invention is to provide an improved sifter, embodying a pair of compartments, one of said compartments being arranged to receive the fine ashes and the other compartment being arranged to receive the partly burned coal.

A further object of the invention is to provide an improved sifter embodying a housing having a swinging screen, which is arranged below a hopper for sifting the ashes therefrom, the screen being so arranged, as 30 to guide the fine ashes to one compartment and the coarse or partly burnt coal to another compartment, the sifter having an improved means for operating the screen.

A still further object of the invention is 35 to provide an improved sifter of the above character having an adjustable door for the hopper, so as to regulate the feed of the ashes to the oscillating screen.

A still further object of the invention is 40 to provide an improved ash sifter, which is durable and efficient in use, one that is simple and easy to manufacture, and one that can be placed upon the market at a reasonable cost.

45 With these and other objects in view the invention consists in the novel construction, arrangement and formation of parts, as will be hereinafter more specifically described, claimed and illustrated in the accompanying drawing, forming a part thereof in which:

Figure 1 is a side elevation of the improved ash sifter,

Figure 2 is an end elevation of the same, showing parts of the housing in section,

50 Figure 3 is a vertical longitudinal section through the improved sifter,

Figure 4 is a detail fragmentary horizontal cross section through the improved sifter,

Figure 5 is a plan view of the adjustable eccentric shaft,

Figure 6 is a detail cross section taken on the line 6—6 of Figure 4.

Referring to the drawings in detail, wherein similar reference numerals designate corresponding parts throughout the several views the numeral 1 generally indicates the improved ash sifter, which embodies a frame 2 including the upright standards 3 connected adjacent their upper and lower ends by vertical longitudinal 70 transverse bars 4. Side walls 5, end walls 6 and a bottom wall 7 is secured to the standards 3 and the bars by cleats 8 and form a housing or casing for the screen 8. The screen 8 includes the side walls 9 and an end 75 wall 10 and a foraminous bottom wall 11, which can be formed of wire mesh or the like. The screen 8 is suspended from the upper longitudinal bars 4 by rods 12, which have the terminals thereof provided with 80 eyes 13, which are adapted to receive the hooks 14 which are carried by the side walls 9 of the screen and hooks 15 carried by the upper longitudinal bars 4. The rods 12 are arranged in pairs and the forward pair is 85 formed relatively shorter than the rear pair so as to support the screen at an angle. The hooks and eyes support the screen for swinging movement and allows the same to be swung back and forth, so as to allow the 90 ashes to be readily sifted.

A hopper 16 having downwardly inclined end walls 17 and 18 and side walls 19 is secured to braces 20 which extend transversely across the housing. An upper wall 95 21 is provided for the hopper which has an opening 22 therein, by means of which the ashes can be sifted and placed therein. The opening is closed by a door 23 which is hinged as at 24 to the top wall. A suitable 100 handle 25 is provided for the door whereby the same can be swung back on its hinges to allow ashes to be placed in the same. The end wall 17 is provided with an opening 26 at the bottom end thereof, which is 105 adapted to be closed by a sliding door 27, which is mounted in spaced guides 28 and it can be seen that by suitable manipulation of the door the opening 26 can be made larger or smaller so as to regulate the flow 110 of ashes from the hopper. A suitable handle 29 is provided on the upper end of the

door 27, whereby the same can be readily operated. One of the side walls 19 is provided with a pair of spaced openings 30 in which are slidably mounted drawers 31 and 32 which are provided with hand pulls 33. Cleats 34 extend transversely in the bottom wall 7 and form means on which the drawers can slide. Suitable guides 35 are provided for engaging the upper outer edges of the 10 drawers and a central guide 36 is provided for engaging the inner upper edges of the drawers. The central guide 36 includes an inverted V-shaped member 37 secured to the transversely extending brace 38. Secured to 15 the screen 8 adjacent to the lowest end thereof is a downward and forwardly inclined chute 39, which extends under the screen, has its lower end positioned immediately above the drawer 31 and is adapted to guide 20 the fine ashes into the same. Suitable brace rods 40 connects the free end of the chutes 39 with the side walls 9 of the screen 8 and provides a rigid connection between the screen and the chute. The lower end of the 25 screen 8 is positioned directly over the drawer 2 and is adapted to guide the coarse ashes or partly burnt coal into the same.

A pair of bearings 40 are secured to one of the end walls 6 and rotatably receives the 30 eccentric shaft 41. The eccentric shaft 41 is formed of a pair of spaced sections 42 which are connected by a central section 43, which is bolted to the same by suitable fastening elements 44. A portion of the shaft 43 lying 35 between the spaced ends of the sections 42 receive the connecting rod 45, which has its opposite end pivotally connected to the chute 39 adjacent to the rear end thereof as at a triangular block 46 and it will be seen that 40 upon rotation of the shaft 41, the connecting rod 45 will swing the screen 8. When it is desired to vary the stroke of the connecting rod 45 washers 47 or other suitable spacing elements are positioned between the 45 shaft sections 42 and 43, so as to space the shaft section 43 from the sections 42 and thereby increase the stroke of the connecting rod.

Spaced blocks 48 are secured to one of 50 the side walls 5 and support a strip 49 in spaced relation to the side wall, a stub-shaft 50 has its terminals journaled in the side walls 5 and the strip 49 is adapted to be turned by a suitable crank 51. A pulley 52 is keyed to the stub-shaft 50 intermediate 55 the strip 49 of the side wall and connected

to a driven pulley 53 connected by a belt 54. The driven pulley 53 is of less diameter than the pulley 52 and is keyed to the eccentric shaft 41.

The difference in the diameters of the drive pulley 52 and the driven pulley 53 forms means whereby the shaft 41 can be driven at a relatively high speed. A diagonal brace rod 55 extends from one of the 65 upper longitudinal bars 4 to the strips 49 and forms a suitable brace for the same.

In operation of the improved device, the ashes to be sifted are placed in the hopper 16 and the door 27 is adjusted to regulate 70 the feed of the same to the screen and the crank is then rotated, which in turn to the medium of the shaft connecting rod swings the screen back and forth which effectively sifts the ashes and the fine ashes fall through 75 the screen onto the chute 39, which carries the same into the drawer 31 and the coarse ashes and partly burnt coals fall in the drawers 31. The drawers can be readily removed, when the same are full.

In practice, I have found that the form of my invention, illustrated in the accompanying drawings and referred to in the above description, as the preferred embodiments, is the most efficient and practical; yet realizing the conditions concurrent with the adoption of my device, I desire to emphasize the fact that various minor changes in detail of construction, proportion and arrangement of parts may be resorted to, when required, without sacrificing any of the advantages of my invention as set forth.

What I claim as new is:

In a sifter, a sifter member, a discharge chute extending angularly therefrom, a reinforcing and securing block of substantially triangular shape in cross section, said block having its apex at the junction of said member and chute with two of its sides in supporting contact respectively with said member and said chute, an operating member secured to and extending from the other side of said block, and said operating member passing snugly through said chute to constitute a reinforcement therefor.

In testimony whereof I affix my signature in presence of two witnesses.

GUSTAVE ERIC ERICKSON.
